ELECTRIC TIMING SYSTEM

John C. Wilson, Bayside, N. Y., assignor to
Hazelton Corporation, a corporation of Delaware

Application August 26, 1938, Serial No. 226,875

10 Claims. (CL 19—44)

This invention relates generally to electrical timing systems and more particularly to timing systems of special utility in television signal-translating apparatus.

It is frequently desirable to time an event in an electrical circuit by means of an electrical pulse and to time a second event a predetermined interval after the first pulse. Such timing systems are particularly useful in modulated-carrier television-signal transmitters, certain of the timing pulses forming component parts of the transmitted signal. In such transmitters, it is customary to generate high-frequency waves which are stabilized with respect to the source of alternating current at the transmitter and to derive therefrom submultiple-frequency waves to be used for various timing operations necessary to generate and transmit the composite television signal. For example, in developing and transmitting a television signal involving double-interlaced scanning and 441 lines per second, it is customary to develop a high-frequency wave, for example, 26,460 cycles, which is stabilized with respect to a source of 60 cycle power supplying the transmitter. From this high-frequency wave a submultiple-frequency wave of 13,230 cycles is developed and utilized to produce line-frequency synchronizing pulses for the transmitted signal. By a further series of subdivisions, a 60 cycle wave is developed and utilized to provide field-frequency synchronizing pulses for the transmitted signal.

A high degree of accuracy is essential in establishing the frequencies of the different wave generators which go to make up the timing chain of the system just described. For this reason it has been customary to develop the waves in the manner described above rather than to generate waves of increasingly higher frequencies from the low-frequency source supplying the transmitter.

However, in subdividing a generated high-frequency wave to derive the waves of lower frequency, it is difficult to secure generators or frequency dividers for each of the steps which are not subject to some inaccuracy. If a particular wave generator of lower frequency is to produce pulses of a frequency of

50

 $\frac{1}{n}$

times that of a higher frequency control wave, it is customary to provide a control circuit for the generator which is responsive to pulses in the control wave which are separated by $n-1$ pulses.

The way of accomplishing this is to provide a relaxation oscillator including a vacuum tube comprising an electrode to which is applied the control wave and which is unaffected by undesired pulses. The frequency of relaxation oscillators utilized in such prior art timing arrangements is, in general, controlled by the time constant of a resistance-reactance circuit. Resistance is an unstable electrical parameter because it depends mainly upon materials and operating conditions. The previous difficulties with relaxation oscillators have resided in an inability to secure an accurately predetermined period and at the same time maintain the oscillator susceptibility of stable synchronization by control pulses. 15

It is an object of the present invention, therefore, to provide an electrical timing system not subject to the above-mentioned disadvantages.

It is a further object of the invention to provide a timing arrangement for deriving from a predetermined control pulse a second pulse having an accurately predetermined time delay with respect to the first pulse. 20

It is still another object of the invention to provide an electrical timing arrangement for deriving from a predetermined timing pulse a second timing pulse of either polarity with respect to the first timing pulse and which has an accurately predetermined time delay with respect to the first pulse. 25

It is a still further object of the invention to provide an electrical timing circuit, the timing of which depends only on the reactive constants of the circuit. 30

In accordance with the invention, an electrical timing system for deriving from a predetermined timing pulse a second timing pulse having a predetermined time delay with respect to the first timing pulse comprises a confluent wave filter having a band-pass which includes the principal frequencies of the first timing pulse, the filter having a mismatched termination at its remote end so that there is procured a reflection of the input pulse from the remote end of the filter. The filter is designed to have an approximately uniform time delay over the pass band equal to one-half of the required time delay of the second impulse. The input end of the filter is terminated in its image impedance so that there is no reflection therefrom. A reflected pulse may, therefore, be derived from the input terminals of the filter a predetermined time after the timing or first pulse has been applied to the input terminals. 45

In accordance with a preferred embodiment 50

55

of the invention, the filter is coupled at the mismatched termination to an impedance much greater than its proper matching value, for example, it may be open-circuited, in which case 5 the reflected pulse appears at the input terminals with the same polarity as that of the first timing pulse. In accordance with another embodiment of the invention, the filter is terminated in an impedance much less than its 10 normal matching value, for example, it may be short-circuited, in which case the second pulse appears at the input terminals of the filter with opposite polarity to the first timing pulse applied to the terminals. 15 The novel features which are believed to be characteristic of this invention are set forth with particularity in the appended claims, the invention itself, however, both as to its organization and method of operation, together with other 20 and further objects thereof, will best be understood by reference to the following description taken in connection with the accompanying drawings, and its scope will be pointed out in the appended claims. 25 Reference is made to the drawings in which Fig. 1 is a circuit diagram of a timing filter of the invention; Figs. 1a and 1b are graphs illustrating certain of the operating characteristics of the circuit of Fig. 1; Fig. 2 is a circuit diagram of the 30 filter of another embodiment of the invention; Figs. 2a and 2b illustrate certain operating characteristics of the circuit of Fig. 2; Fig. 3 is a circuit diagram of a timing filter of the invention utilized for deriving a broad timing impulse; Fig. 35 3a illustrates certain of the operating characteristics of the circuit of Fig. 3; Fig. 4 illustrates the method by which the timing signals of a standardized television signal may be synthesized, utilizing timing circuits in accordance with the 40 invention; while Fig. 5 illustrates the manner in which the circuit of the invention may be utilized in a television receiving system as a synchronizing-signal separator.

Referring now more specifically to Fig. 1, there 45 is shown a low-pass filter comprising input terminals 10 to which is coupled an impedance-matching m-derived half section including a series arm comprising an inductance L_1 and a shunt arm comprising a series-connected inductance L_2 and 50 condenser C_2 , a series of constant-k whole sections individually comprising series inductance arms L_3 and shunt condenser arms C_3 , and a mid-shunt element

$$\frac{C_1}{2}$$

The filter of Fig. 1 is terminated at the input terminals 10 by an impedance shown as a resistance R which approximately matches the input image 55 impedance of the filter over the pass band, while the filter is open-circuited at the remote end; that is which is that of the impedance-matching m-derived section including series arm L_1 and shunt arm L_2, C_2 , at the terminals 11 remote from 60 input terminals 10, the filter has a mismatched termination.

In considering the operation of the circuit of Fig. 1, reference is made to Figs. 1a and 1b. The graph of Fig. 1a represents a timing impulse 65 which may be applied to input terminals 10 and from which it is desired to derive a similar timing impulse of the same polarity delayed a predetermined interval with respect to the timing impulse of Fig. 1a. It will be assumed that the pass band 70 of the circuit of Fig. 1 is sufficiently broad to pass

the principal frequencies of the timing impulse of Fig. 1a and that the timing impulse is applied to the terminals 10. Due to the fact that there is an improper termination or mismatching at the end of the filter remote from terminals 10, an 5 electrical impulse which is the image of the applied impulse is reflected from the terminals 11 and appears, after a predetermined delay, across the input terminals 10. The time delay of the filter is made one-half of the desired time delay 10 and the filter is terminated at the input terminals 10 in its image impedance R so that there is no further reflection of the echo or reflected impulse. These characteristics are illustrated by the graph of Fig. 1b in which a represents the first timing 15 pulse initiating at time t_0 and b represents the second timing pulse which appears across terminals 10 at time t_1 , that is, with a predetermined time delay Δt with respect to the initial impulse a . 20

If it is desired to derive from a first impulse a second impulse of opposite polarity to that of the first impulse, the circuit of Fig. 2 is utilized. The filter of Fig. 2 is generally similar to that of Fig. 1 and similar circuit elements have been given identical reference numerals. The circuit of Fig. 2 differs from that of Fig. 1 only in that the filter is short-circuited at the terminals 11 instead of being open-circuited, as in the case of the filter 25 of the circuit of Fig. 1.

The operation of the circuit of Fig. 2 is generally similar to the operation of the filter of the circuit of Fig. 1 except that the second derived timing pulse, present at the input terminals 10 at time t_1 , is of opposite polarity to that of the first timing pulse applied at t_0 as indicated in Figs. 2a 30 and 2b.

A broad pulse may be derived from the pulse a shown in Figs. 1a or 2a having a duration Δt , by utilizing the characteristic of the circuit of Fig. 2 together with a suitable integrating arrangement. 40 One circuit for deriving such a broad pulse is shown in Fig. 3, wherein the filter coupled to the input terminals 10 is in all respects similar to that of Fig. 2. Coupled to the terminals 10 through a transformer 12 is a wave generator comprising a 45 condenser 13 and circuits for charging and discharging condenser 13 from a suitable source such as battery 14, the charging and discharging circuits being responsive to the timing pulses derived from the filter. The charging circuit for condenser 13 comprises a vacuum tube 15 having its input electrodes connected across a portion of the secondary winding of transformer 12 and its output electrodes connected in series with condenser 13 and battery 14. The discharging circuit of 50 condenser 13 comprises a second vacuum tube 16 having its input electrodes coupled across a portion of the secondary winding of transformer 12 and its output electrodes connected to short circuit condenser 13. The control circuit of Fig. 3 55 comprising transformer 12 is designed so that the filter 11 is terminated substantially in its image impedance at terminals 10.

In considering the operation of the circuit of Fig. 3, it will be assumed that a timing impulse of 60 the form a of Fig. 2a is applied to the input terminals 10. It will thus be seen that a reflected wave having the characteristics of impulse b of Fig. 2b may be derived from input terminals 10 after the predetermined interval Δt . Tube 15 is so biased 65 that it becomes conductive only when impulse a is applied to its grid and charges condenser 13 which remains charged until such time as tube 16 becomes conductive to discharge the condenser. Tube 16 is rendered conductive by the negative 70

75

5 pulse *b* of Fig. 2*b* which is applied to its grid with reversed or positive polarity by transformer *12*. An output voltage pulse may, therefore, be derived from condenser *13* which has the wave form shown in Fig. 3*a*.

10 It will be understood that each of the filters is terminated at terminals *10* in its image impedance *R* which may be comprised in whole or in part in the circuit constants of the external circuits coupled to the terminals *10*.

15 The circuits of the invention are particularly useful in deriving a wave of the form of the proposed standardized synchronizing wave for television-signal transmitters. This wave form is completely described in an article entitled "R. M. A. Completes Television Standards" in the July, 1938 issue of "Electronics" at pages 28 and 29. A portion of the proposed standardized wave form is shown in curve *A* of Fig. 4. This wave 20 comprises line-scanning synchronizing pulses *s*, equalizing pulses *e* of half the width of synchronizing pulses *s*, and broad field-scanning synchronizing pulses *v* combined in a manner described in the above-mentioned article. A wave of the 25 type shown in curve *A* of Fig. 4 may be derived by means of synthetic pulses developed in accordance with the principles described in the preceding portion of the specification. In order to produce such a wave, there are developed pulses 30 of a constant period and duration, as shown in curve *B*, which are of the width of the equalizing pulses *e* of composite wave *A* and which are spaced by the interval between line-synchronizing pulses in the desired wave *A*. Certain of the 35 pulses of wave *B* are selected for reflection, as shown by curve *C*, in the manner described above for obtaining a positive reflected impulse (see Fig. 1), the period of delay being exactly equal to the pulse width. Certain of the other pulses 40 are selected for reflection as shown in curve *D*, the period of delay being one-half the horizontal scanning period; that is, one-half the spacing of the pulses of curve *B*. Certain of the pulses of curve *B* are selected and combined with certain 45 of the pulses of curve *D* as shown by curve *E* and are then inversely reflected (see Fig. 2) with a delay of about four-tenths of the horizontal synchronizing period, thereby producing the wave shown by curve *F*. By integrating the waves of 50 curves *E* and *F* in the manner described with reference to Fig. 3 above, the group of broad field-synchronizing impulses shown by curve *G* is obtained. By combining the wave forms of 55 curves *B*, *C*, *D* and *G*, and limiting in a suitable and known manner, the proposed standardized wave form *A* may be built up.

The timing circuits of the invention may be utilized for separation of synchronizing signals in a similar manner. Thus, the line-synchronizing signals may be separated from the field-synchronizing signals by the following procedure: In an apparatus for performing this function it is desirable to obtain a precisely timed impulse suitable for field synchronizing and at the same time to utilize all of the regular pulses to maintain line synchronization. This may be accomplished by reflecting the whole complex synchronizing wave to delay the wave by a predetermined amount to the undelayed complex wave, so determining the 70 delay period that the line-synchronizing and equalizing pulses fall between each other but the field-synchronizing pulses, or parts thereof, fall on top of their counterparts. The double amplitude of the resultant field-synchronizing pulses 75 provides a precisely timed impulse for field syn-

chronization. The characteristics obtained by such procedure are illustrated by the curves of Fig. 5 wherein curve *H* represents the undelayed complex wave, curve *I* illustrates the delay complex wave, and curve *J* illustrates the resultant of the two waves *H* and *I*. It is thus seen that the complex timing wave *H* may be used in the normal manner to maintain horizontal synchronization and that a timing impulse of increased amplitude of curve *J* may be utilized to effect field synchronization.

10 While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

15 What is claimed is:

1. An electrical timing system for deriving from a given timing pulse a second timing pulse having a predetermined time delay with respect to said first pulse comprising, a wave filter having input terminals and having a pass band including the principal frequencies of said first pulse, said filter having a mismatched termination remote from said terminals and having an approximately uniform time delay between said terminals and said termination over said pass band equal to a predetermined fraction of said predetermined time delay, an output circuit coupled to said filter for deriving said second pulse, and an impedance-matching filter section 30 terminating said filter at the end opposite said mismatched termination and approximately matching the image impedance of said filter with said output circuit over said pass band.

2. An electrical timing system for deriving from a given timing pulse a second timing pulse of the same polarity having a predetermined time delay with respect to said first pulse comprising, a wave filter having input terminals and having a pass band including the principal frequencies of said first pulse, said filter having a termination remote from said terminals of an impedance appreciably greater than its image impedance at such termination and having an approximately uniform time delay between said terminals and said termination over said pass band equal to a predetermined fraction of said uniform time delay, an output circuit coupled to said filter for deriving said second pulse, and an impedance-matching filter section 45 terminating said filter at the end opposite said termination and approximately matching the image impedance of said filter with said output circuit over the pass band of said filter.

3. An electrical timing system for deriving from a given timing pulse a second timing pulse of the same polarity having a predetermined time delay with respect to said first pulse comprising, a wave filter having input terminals and having a pass band including the principal frequencies 60 of said first pulse, said filter having an open-circuited termination remote from said terminals and having approximately uniform time delay between said terminals and said termination over said pass band equal to a predetermined fraction of said predetermined time delay, an output circuit coupled to said filter for deriving said second pulse, and an impedance-matching filter section 65 terminating said filter at the end opposite said open-circuited termination and approximately 70

75

matching the image impedance of said filter with said output circuit over said pass band.

4. An electrical timing system for deriving from a given timing pulse a second timing pulse of opposite polarity having a predetermined time delay with respect to said first pulse comprising, a wave filter having input terminals and having a pass band including the principal frequencies of said first pulse, said filter having a termination remote from said terminals coupled to an impedance appreciably less than its image impedance at such termination and having an approximately uniform time delay between said terminals and said termination over said pass band equal to a predetermined fraction of said predetermined time delay, and an output circuit coupled to said filter for deriving said second pulse, said filter being terminated at the end opposite said termination in an impedance approximately matching its image impedance over said pass band.
5. An electrical timing system for deriving from a given timing pulse a second timing pulse of opposite polarity having a predetermined time delay with respect to said first pulse comprising, a wave filter having input terminals and having a pass band including the principal frequencies of said first pulse, said filter having a termination remote from said terminals equal to a predetermined fraction of said predetermined time delay, and an output circuit coupled to said filter for deriving said second pulse, said filter being terminated at the end opposite said termination in an impedance approximately matching its image impedance over said pass band.

6. An electrical timing system for deriving from a given timing pulse a second timing pulse having a predetermined time delay with respect to said first pulse comprising, a wave filter having input terminals and having a pass band including the principal frequencies of said first pulse, said filter having a termination remote from said terminals which is short-circuited and having an approximately uniform time delay between said terminals and said termination over said pass band equal to a predetermined fraction of said predetermined time delay, and an output circuit coupled to said filter for deriving said second pulse, said filter being terminated at the end remote from said short-circuited termination in an impedance approximately matching its image impedance over said pass band.

7. An electrical timing system for deriving from a given timing pulse a second timing pulse having a predetermined time delay with respect to said first pulse comprising, a wave filter having input terminals and having a pass band including the principal frequencies of said first pulse, a resistance termination for said filter, a matching filter section for said filter coupled to said filter at one end and having an impedance approximately matching the image impedance of said filter to said resistor over said pass band, said filter having a mismatched termination at the other end and having an approximately uniform time delay between said terminals and said other end over said pass band equal to a predetermined fraction of said predetermined time delay, and an output circuit coupled to said filter for deriving said second pulse.

8. An electrical timing system for deriving from a given timing pulse a second timing pulse having a predetermined time delay with respect to said first pulse comprising, a wave filter having input terminals and having a pass band including the principal frequencies of said first pulse, a resistance termination for said filter at one end, said filter comprising an m-derived section coupled to said resistance termination and matching the impedance of said filter with said termination over said pass band, said filter having a mismatched termination at its other end remote from said terminals and having an approximately uniform time delay over said pass band between said terminals and said other end equal to a predetermined fraction of said predetermined time

delay, and an output circuit coupled to said filter for deriving said second pulse.

9. An electrical timing system for deriving from a given timing pulse a second timing pulse of opposite polarity having a predetermined time delay with respect to said first pulse comprising, a wave filter having input terminals and having a pass band including the principal frequencies of said first pulse, said filter having a termination remote from said terminals coupled to an impedance appreciably less than its image impedance at such termination and having an approximately uniform time delay between said terminals and said termination over said pass band equal to a predetermined fraction of said predetermined time delay, an output circuit coupled to said filter for deriving said second pulse, and means coupled to said filter for deriving a broad pulse from said two pulses of opposite polarity, said filter being terminated at the end opposite said termination in an impedance approximately matching its image impedance over said pass band.

10. An electrical timing system for deriving from a given timing pulse a second timing pulse of opposite polarity having a predetermined time delay with respect to said first pulse comprising, a wave filter having input terminals and having a pass band including the principal frequencies of said first pulse, said filter having a termination remote from said terminals coupled to an impedance appreciably less than its image impedance at said termination over said pass band and having an approximately uniform time delay between said terminals and said termination over said pass band equal to a predetermined fraction of said predetermined time delay, an output circuit coupled to said filter for deriving said second pulse, and pulse-generating means coupled to said filter comprising capacitance means, means for charging said capacitance means in response to one of said timing pulses and for discharging said capacitance means in response to the other of said timing pulses, said filter being terminated at the end remote from said termination in an impedance approximately matching its image impedance over said pass band.

11. An electrical timing system for deriving from a given timing pulse a second timing pulse of opposite polarity having a predetermined time delay with respect to said first pulse comprising, a wave filter having input terminals and having a pass band including the principal frequencies of said first timing pulse, said filter having a termination remote from said terminals coupled to an impedance appreciably less than its image impedance at said termination over said pass band and having an approximately uniform time delay between said terminals and said termination over said pass band equal to one-half said predetermined time delay, an output circuit coupled to said filter for deriving said second pulse, pulse generating means coupled to said filter including capacitance means, means comprising a vacuum tube responsive to one of said pulses for charging said capacitance means, and means comprising a vacuum tube responsive to the other of said pulses for discharging said capacitance means, said filter being terminated at the end remote from said termination in an impedance approximately matching its image impedance over said pass band.

JOHN C. WILSON.

CERTIFICATE OF CORRECTION.

Patent No. 2,188,970.

February 6, 1940.

JOHN C. WILSON.

It is hereby certified that error appears in the printed specification of the above numbered patent requiring correction as follows: Page 1, second column, line 1, for "The way" read The usual way; page 2, first column, lines 62, 63 and 64, strike out "which is that of the impedance-matching m-derived section including series arm L_1 and shunt arm L_2, C_2 " and insert the same in line 60, after "band" and before the comma; and that the said Letters Patent should be read with this correction therein that the same may conform to the record of the case in the Patent Office.

Signed and sealed this 9th day of April, A. D. 1940.

Henry Van Arsdale,

(Seal)

Acting Commissioner of Patents.
